CLEANING APPARATUS FOR LAMP SHADES
HAVING A ROTARY SUPPORT, FLUID
SPRAY, AND DRIER

Wallace C. Douglass, Tuckahoe, N. Y.

Application May 31, 1946, Serial No. 673,422

4 Claims.

(Cl. 68—20)

1

This invention relates to cleaning devices or apparatus and particularly to apparatus for supporting and cleaning any desired articles to be cleaned and the particular object or article selected for illustration is a lamp shade. It should be understood, however, that the apparatus may be used for supporting and cleaning many other articles, which cannot be immersed, by spraying the articles with the cleaning fluid and removing the cleaning fluid by spinning or rotating the article cleaned.

Lamp shades formed of silk or similar textile material are difficult to clean satisfactorily by the usual cleaning methods since in drying they become streaked and rusted. For this reason most cleaners refuse to clean lamp shades and those who do clean them charge at a high rate because of the amount of hand labor required.

This invention has for its salient object to provide simple, practical and efficient apparatus for easily, quickly and effectively cleaning and drying articles to be cleaned.

Another object of the invention is to provide apparatus of the character described so constructed and arranged that practically no hand labor is required and the articles will be cleaned and dried without streaking.

Further objects of the invention will appear from the following specification taken in connection with the drawings which form a part of this application, and in which

Fig. 1 is a vertical sectional elevation of the apparatus constructed in accordance with the invention;

Fig. 2 is a detail sectional elevation of the control valve, this view being taken substantially on line 2—2 of Fig. 1, looking in the direction of the arrows;

Fig. 3 is a view similar to Fig. 1 but illustrating a modified construction of shade mounting; and

Fig. 4 is a top plan view of the shade supporting and clamping means.

In the particular form of the apparatus illustrated in Figs. 1 and 2 there is shown a casing 10 which is mounted in a base 11 which supports a motor M below the casing.

The motor M has an upwardly extending shaft 12 on which is fixed the hub 13 of a support 14 which is preferably in the form of a spider having arms 15 extending radially of the hub 13 and shaft 12. The hub 13 is mounted on a thrust bearing 16. The arms 15 are provided on their upper surfaces with a layer 17 of cushioning material, such as soft rubber. A suitable packing or gasket is provided at 18 around the shaft 12 to prevent leakage of the cleaning and rinsing fluids.

It will be noted that the bottom of the casing slopes downwardly toward the outer edge and

2

an outlet pipe 20 is connected to this lower portion of the casing for draining out the cleaning fluid and rinsing fluid and permitting the escape of drying air.

In order to secure the article to be cleaned, such as a lamp shade, on the support 14, the lamp shade indicated by dot and dash lines at 21 is mounted on the support with the usual washer or collar 21' of the shade disposed over the shaft 12 and secured to the shaft by a clip 22 having a reduced or inwardly bent portion 23 engaging an annular groove 24 in the upper end of the shaft 12.

The top of the casing is closed by a closure member or cover 30 which is suitably secured to the top by means of a toggle clamping means 31, one of these clamping means being shown in Fig. 1. It will be understood that other similar clamps may be used or the cover may, if desired, be hinged to the top of the casing.

The closure member or cover 30 has secured thereto a conduit 35 which extends down into the casing when the cover is secured to the casing and is provided with perforations 36 through which the cleaning fluid is sprayed on the wall of the lamp shade.

Suitable means is provided for conducting to and through the conduit 35 cleaning fluid, rinsing fluid and drying air. In the form of the invention shown there is illustrated a valve which is secured to a flexible hose or pipe 37 which is connected at its lower end to the upper end of the conduit 35. The valve comprises a casing or housing 40 having an outlet conduit 41 communicating with the pipe 37 and having a central laterally extending portion 42 communicating with a conduit 43 formed in a rotatable, substantially cylindrical, valve member 44 mounted in the valve casing 40. The rotatable valve member 44 has a spindle 45 extending through the wall of the casing and on the outer end of this spindle there is mounted a valve handle 46.

The valve casing 40 has connected to the wall thereof three conduits 50, 51 and 52 which are adapted respectively to conduct to the casing, cleaning fluid, rinsing fluid or water, and hot air for drying. The wall of the casing is provided with openings in alignment with the conduits 50, 51 and 52.

When the valve is turned to the position shown in Fig. 1 and indicated as "off," no fluid will be conducted through the valve to the pipe 37. When the valve handle is turned in a clockwise direction to align the conduit 43 with the conduit 41 or to the position indicated by the term "soap," cleaning fluid will be conducted through the valve to the pipe 37. It should be understood that any desired fluid may be used.

When the handle is turned to align the conduit

43 with the pipe 51, or to the position indicated on Fig. 1 by the term "water," rinsing fluid will be conducted through the valve to the pipe 31.

When the valve handle is turned to align the conduit 43 with the conduit 52, air, and preferably warm air, under pressure will be conducted through the valve to the pipe 31.

It will be understood that suitable pressure means will be provided for pumping cleaning fluid, rinsing fluid and hot air through the valve to the pipe 31 and conduit 35.

Figs. 3 and 4 illustrate a slightly different form of clamping structure and support for the lamp shade. The motor M is mounted on a base 51 similar to the base 11 in Fig. 1. Above the base 51 is mounted a supporting structure or frame 52 having a central opening 53 which receives a sleeve 54. The sleeve 54 is slidably axially in the opening 53 and on motor shaft 55 which extends upwardly therethrough. A packing 57 surrounds the sleeve 54 and is held in position by a threaded sleeve 58. The sleeve has a supporting table or hub 60 on the periphery of which are mounted arms 61, preferably resilient, and on the outer ends of the arms is mounted a ring 62 covered with cushioning material 63.

Shaft 55 is splined to the sleeve, as shown at 56, so that the sleeve can slide axially on shaft 55 but will be driven thereby. A packing 65 is provided at the entrance to the central opening or bore 66 through the hub or support 60 and sleeve 54.

The sleeve 54 is normally forced upwardly on shaft 55 by a spring 67 which surrounds the shaft 55 and is positioned between a collar 68 adjustably mounted on shaft 55 and the lower end of sleeve 54. The upper end of shaft 55 is threaded, as shown at 69, and a dished spider 70 comprising arms 71 and a cushioned ring 72 at the ends of the arms is mounted on the threaded portion 69. A wing nut 73 engages the spider 70 and causes the ring 72 to press the arms 74 of the lamp shade 75 against the ring 62. The spring 67 forces the sleeve 54, hub 60, arms 61, and ring 62 upwardly against the lamp shade arms 74.

The remaining parts of the structure shown in Figs. 3 and 4 are the same as those shown in Figs. 1 and 2, and need not be further described.

During the operation of the valve the motor M will be operated to rotate the support 14 and lamp shade or other article clamped thereon and suitable control means will be provided for the motor so that the speed of the motor may be varied as desired and the motor will preferably be speeded up during the drying operation.

It will be evident that as the shade is rotated and the cleaning fluid is sprayed thereon in the manner above described, this fluid will be forced through the shade by centrifugal force and will drop to the sump or lower portion of the casing 10 and be drained therefrom through the pipe 20. After the cleaning fluid has been used, the valve is rotated to the position to conduct rinsing water or fluid through the pipe 31 and conduit 35 and this rinsing water will also be forced through the shade by centrifugal force. Thereafter the valve will be operated to conduct hot air under pressure to the casing and the centrifugal force combined with the hot circulating air will carry off the moisture and will effectively dry the shade and wire. When thus washed and dried the shade or article cleaned will not be streaked as in the usual cleaning operations and the wire will not rust due to inefficient drying.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What I claim is:

- 10 1. Cleaning and drying apparatus for lamp shades comprising a container, a shaft extending centrally into said container, means for rotating said shaft, a substantially horizontal supporting base mounted on said shaft for rotation therewith and spaced from the bottom of the container, centrally located releasable devices interfittingly engaged with said shaft above said support for engaging the central portion of a lamp shade and clamping said shade on said support, the space 15 in the container above and laterally beyond the support being free and unobstructed, and means for conducting cleaning and rinsing fluid and air into said container and against the shade mounted on said support.
- 20 2. Cleaning and drying apparatus comprising a container, a rotatable shaft extending into the container and disposed centrally therein, a support mounted on the shaft in the lower portion of the container, and comprising arms extending substantially radially from the shaft, a clamp axially adjustably mounted on the shaft above the support for engaging the central portion of an article and clamping the article on the shaft and supporting arms, said shaft, clamp and arms 25 forming the sole support for the article and the space around the article in the container being free and unobstructed, means for conducting cleaning and rinsing fluid against the article so supported, and means for rotating the shaft and support in the container.
- 30 3. Cleaning and drying apparatus as in claim 1, wherein the releasable devices include a spring clip and an annular groove in the shaft adjacent its upper end into which portions of the clip are releasably received.

- 35 4. Cleaning and drying apparatus as in claim 3, wherein the end of the shaft above the support is threaded and said releasable devices include a dished spider loosely mounted on the threaded end of the shaft over the lamp shade and a nut threaded on the shaft to move the spider into holding engagement with the lamp shade being cleaned.
